UNITED STATES PATENT OFFICE.

PETER McGURK, OF WILLIAMSBURG, NEW YORK.

IMPROVEMENT IN TOY PUZZLE-BOXES.

Specification forming part of Letters Patent No. **158,106**, dated December 22, 1874; application filed July 10, 1874.

To all whom it may concern:

Be it known that I, PETER McGURK, of Williamsburg, county of Kings, State of New York, have invented certain Improvements in Puzzle-Boxes, of which the following is a specification:

The object of my invention is to provide a puzzle-box which can be cheaply constructed and easily operated.

In order to describe my invention more fully, I refer to the accompanying drawing, forming a part of this specification.

Figure I is a plan view of my improved puzzle-box, when one of the inner boxes is drawn out. Fig. II is a sectional view of the same, taken on line $x-x$, Fig. I. Fig. III is a sectional view taken on line $x-x$, Fig. I, when both the inner boxes are drawn out.

A is the outer box or casing, open at a^1 and closed at a^2 . Into the drawer-box A slides another drawer-box, B, having on the upper side an opening, b^1 , which is covered with a lid, b^2 , hinged to the box. This box is closed at the outer end and left open at the inner, for the reception of a third box, C, which will be hereafter described. To the under side of box B, and near the inner end, is formed a shoulder, b^3 , which rests against shoulder a^3 of box A, in order to prevent the box B from sliding too far out. a^6 are handles, by which the box B is drawn out or pushed in. The box C is closed at both ends, but the top is left open. The inner end of this box is provided with a shoulder, c^1 , which locks itself behind the notch a^4 , and holds the box C in the position as

shown in Fig. II. In order to hold the box C still more securely in this position, there is placed a guide, a^5 , sliding in grooves c^2 .

The operation of my invention is as follows: Draw the boxes out, as shown in Fig. III, open the lid, and place any small object in the box C; then close the lid and push the boxes back again into the casing. It will then be seen that box C will lock itself behind notch a^4 . Now, by drawing box B out again, it will be seen that, instead of drawing out box C, you will only draw out box B, which will be empty. When box C is to be drawn out, simply press downward the bottom piece a^7 at e , which is attached loosely to the casing A. By this operation the notch a^4 is withdrawn from the shoulder c^1 , which in turn releases the box C, and allows it to slide out with the box B.

Having thus described my invention, I desire to claim—

The toy box herein described, consisting essentially of the box A with the drawer-boxes B C sliding therein, the shoulders a^3 a^4 b^3 c^1 , the lid b^2 , and the guide a^5 , all combined and arranged to operate substantially as described and shown.

This specification signed this 26th day of June, 1874.

PETER ^{his} + McGURK.
mark.
